UNITED STATES PATENT OFFICE.

ALVA E. RUTTER, OF OTTUMWA, IOWA, ASSIGNOR TO DAIN MANUFACTURING COMPANY OF IOWA, OF OTTUMWA, IOWA, A CORPORATION OF IOWA.

CABLE GUIDE FOR HAYSTACKERS.

Application filed March 21, 1925. Serial No. 17,197.

My invention relates to hay stackers of the type comprising a hoisting means arranged to be raised to lift the load of hay that is to be deposited on the stack, by means 5 of a hoisting cable operated by horse power. In such machines the cable or rope runs over upper and lower sheaves carried by the usual frames that form part of the stacker, and the lower sheave or pulley is usually loosely 10 attached to the stationary frame so that it may swing laterally to enable the team in hoisting to walk away from the stacker at the most convenient angle. The devices heretofore employed for that purpose have, 15 however, not been entirely satisfactory, and one of the objects of my present invention is to provide an improved mounting for the lower sheave by which it will be steadily supported, and at the same time will be free 20 to swing laterally to permit the hoisting rope to be drawn away in any direction. Another of my objects is to provide convenient and effective means for securing or braking the hoisting cable, to hold the load up at any 25 stage of its elevation, but which will be capable of being easily and quickly actuated to release the cable when its release is desired. I accomplish these objects as illustrated in the drawings and as hereinafter 30 described. What I regard as new is set forth in the claims.

In the accompanying drawings, in which I have illustrated only such parts of a stacker as are necessary to an understanding 35 of my invention,—

Fig. 1 is a side elevation of part of the stationary frame of a stacker showing the lower sheave in side elevation also;

Fig. 2 is a similar view partly in vertical 40 section to show the cable braking or locking devices;

Fig. 3 is mainly a plan view of the parts shown in Fig. 1, a part of the frame being in section;

Fig. 4 is a partial vertical cross-section 45 on line 4—4 of Fig. 2; and

Fig. 5 is a perspective view of the cable locking shoe.

Referring to the drawings, 6 indicates 50 one of the side members of the stationary frame of a stacker, on which the usual operating parts, such as a swinging hoisting frame, are mounted, and 7 indicates a fixed upright or standard that rises from said stationary frame. These parts may be of any

approved design, as my invention is not concerned with the particular construction of the stationary frame any further than that it must be such as to provide a suitable support for the parts hereinafter described. 60

Fixedly secured to the side member 6 is a bracket 8 provided with a laterally projecting lug 9 that has a circular vertically disposed passage therethrough, as best shown in Fig. 2. A somewhat similar bracket 10 is fixedly secured to the upright 7, and carries a lug 11 that also projects laterally in position to overlie the lug 9. The lug 11 is likewise provided with a vertically disposed passage arranged in vertical alignment with the passage in the lug 9. Journaled in the bearings provided by these two passages is a sheave supporting bracket 12, the end portions 13, 14 of which are of reduced diameter and of cylindrical form so that they constitute 70 journals that fit and bear in the passages above referred to, thereby rotatably supporting the sheave supporting bracket 12 so that while it may turn about a vertical axis, it is securely held against vertical movement, 75 as clearly illustrated in Figs. 2 and 3.

The upper portion of the bracket 12 has an axial passage 15 therethrough, and preferably a similar passage 16 is provided in the lower portion thereof, the inner ends of 80 which passages merge into a concavity 17 at the intermediate portion of said bracket, as shown in Fig. 2. At opposite sides of this concavity are two parallel members 18, 19, that are integral with the axial portion of the bracket, and project laterally to provide a support for a sheave 20, which is mounted to rotate upon an axle 21 the ends of which are secured to the members 18, 19 respectively. Preferably anti-friction bearings 90 are provided between the hub of the sheave 20 and the axle 21, as shown in Fig. 2. It will be noted that the parts are so proportioned and arranged that a portion of the sheave lies in the concavity 17 substantially 95 in tangential relation to the axis of the passage 15.

The sheave 20 is provided with a peripheral groove 23, as shown in Fig. 3, to receive the hoisting rope or cable 24, which runs 100 around the under and inner portion of said sheave, and passes upward therefrom through the axial passage 15, to an operative connection, in any suitable way, with the load supporting and lifting element of the 105 110

stacker, which may be of any approved design, such as a swinging hoisting frame. The opposite end of the cable is arranged to be hitched to a team, so that the draft 5 operates to rotate the sheave in a clock-wise direction as viewed in Fig. 2. Below the sheave the bracket 12 is provided with a laterally extending member 25 constituting a bottom wall that underlies the sheave and 10 has a concave upper surface that may substantially conform to the curvature of the sheave and is adjacent thereto, which surface is longitudinally grooved to provide a better gripping surface for the cable 24. 15 As best shown in Fig. 1, the member 25, with those parts of the bracket 12 that partially enclose the sheave 20, constitute a housing for the portion of the sheave with which 20 is capable of swinging laterally with the sheave about a vertical axis coincident with the load sustaining portion of the cable, which, therefore, is not affected by such lateral swinging.

As it is desirable that means be provided whereby the hoisting frame of the stacker may when necessary be locked against descent, for that purpose I provide a braking shoe or wedge block 26 the construction of 25 which is best shown in Figs. 3 and 5. Said shoe is in the form of a sector the inner surface of which is curved to conform to the curvature of the sheave 20, and is shaped to fit closely in the groove 23, as shown in 30 Figs. 2 and 3. Said shoe is, however, detached from the sheave so that it is entirely free to be moved radially relatively thereto to vary its frictional engagement therewith, or to be laid aside when not required for use 35 so that then it will not interfere with the free movement of the cable in either direction. The outer surface of said shoe is provided with a longitudinal tapered groove 27 that preferably commences near the middle 40 of the shoe and gradually grows wider and deeper until it runs out at one end of the shoe, which, in operation, is its inner end, as shown in Fig. 2, thereby providing said shoe with a wedge-shaped portion 28. This 45 shoe is adapted to be applied to the groove of the sheave 20 between the sheave and the draft end portion of the cable 24, so that when the cable is paid out to lower the load, at which time the sheave rotates in a counter-clockwise direction as viewed in Fig. 2, the 50 inner end of the shoe will, by its frictional engagement with the sheave and the cable, be carried around between the sheave and the cable and into the space between the 55 sheave and the member 25 of the housing, thereby forcing the cable away from the inner face of the member 25. Thus a very effective 60 brake is provided which stops descent of the load and will hold it up indefinitely. To

release the load so that it may descend it is necessary only to apply sufficient draft to the cable to permit the shoe to be withdrawn, since the draft rotates the sheave in the opposite direction and carries the shoe out 70 of its operative position. It will be noted that the side and bottom walls of the housing member 25 serve as supporting means for the detachable shoe, holding the same laterally and vertically against displacement 75 when the shoe is in operative position in the sheave, and the bottom wall also serving as a gripping surface against which the cable is forced by the shoe in the wedging action of the latter. As the shoe is not attached 80 to the sheave, when not required for use it may be removed and laid aside, so as not to restrict the movement of the cable in either direction. The shoe is preferably attached to the housing by a chain 29, so that it will 85 always be available for use when needed. Obviously lateral swinging of the sheave does not interfere with the operation of the locking or braking device.

What I claim as my invention and desire 90 to secure by Letters Patent, is—

1. A cable guide for hay stackers comprising upper and lower brackets fixedly secured to the stacker frame and having vertically aligned passages, a sheave supporting 95 bracket having upper and lower co-axial journals mounted to rotate in said passages, an axially disposed passage through the upper journal for the hoisting cable, means for pivotally supporting a sheave having a 100 peripheral groove substantially in tangential relation to the latter passage, a housing enclosing the cable engaging portion of the sheave and having a laterally projecting member that extends under the sheave opposite the groove therein, and a detached shoe 105 adapted to fit in said groove and to be projected between the sheave and said laterally projecting member to grip the cable between 110 said member and the outer surface of said shoe.

2. A cable guide for hay stackers comprising upper and lower brackets fixedly secured to the stacker frame and having vertically aligned passages, a sheave supporting 115 bracket having upper and lower co-axial journals mounted to rotate in said passages, an axially disposed passage through the upper journal for the hoisting cable, means for pivotally supporting a sheave having a 120 peripheral groove substantially in tangential relation to the latter passage, a housing enclosing the cable engaging portion of the sheave and having a laterally projecting member that extends under the sheave opposite the groove therein, and a detached shoe 125 adapted to fit in said groove and to be projected between the sheave and said laterally projecting member to grip the cable between 130 said member and the outer surface of said

shoe, said shoe having a groove in its outer surface tapered in depth and width, to receive the cable.

3. In a hoisting device, the combination with a sheave and a bracket pivotally supporting said sheave to swing about a vertical axis, said bracket comprising a bottom wall curved substantially concentrically with the periphery of said sheave and having an intermediately disposed concavity in its curved upper face, of a detached shoe adapted to be applied to the sheave between the periphery thereof and the cable, and to project over said bottom wall and operable by its frictional engagement with the sheave to clamp the cable against the concavity in said bottom wall when the sheave is rotated to lower the load.

4. A cable guide for hay stackers comprising upper and lower brackets fixedly secured to the stacker frame and having vertically aligned passages, a sheave supporting bracket having upper and lower coaxial journals mounted to rotate in said passages, an axially disposed passage through the upper journal for the hoisting cable, a sheave pivotally supported by said bracket, said sheave having a peripheral groove substantially in tangential relation to the axis of the latter passage, said sheave supporting bracket comprising a bottom wall curved substantially concentrically with the periphery of said sheave and having an intermediately disposed concavity in its curved upper face opposite the groove in the sheave, and a detached shoe adapted to fit in said groove and to extend over said bottom wall to grip the cable in the concavity formed in said wall.

5. A cable guide for hay stackers comprising upper and lower bearing brackets fixedly secured to the stacker frame, said upper bearing bracket having a vertically aligned passage therein, a sheave supporting bracket having upper and lower co-axial journals having bearing engagement with said upper and lower bearing brackets to permit lateral swinging of said sheave supporting bracket, an axially disposed passage through the upper journal for the hoisting cable, a sheave pivotally supported by said latter bracket, said sheave having a peripheral groove substantially in tangential relation to the latter passage, said sheave supporting bracket comprising a bottom wall extending outwardly under the bottom of the sheave in relatively close proximity thereto, and a detached shoe adapted to be applied to the sheave between the periphery thereof and the cable and to be carried inwardly over said bottom wall to grip the cable between the bottom wall and the shoe, said bottom wall also tending to guide the cable to the peripheral groove in said sheave when the shoe is detached.
